United States Patent Office

Des. 178,502
Patented Aug. 14, 1956

178,502

SODA GLASS OR SIMILAR ARTICLE

Richard C. Diebenkorn, Atherton, Calif., assignor to Dohrmann Hotel Supply Co., San Francisco, Calif., a corporation of Nevada

Application January 9, 1956, Serial No. 39,659

Term of patent 14 years

(Cl. D36—8)

Figure 1 is a side elevational view of a soda glass or similar article showing my new design;

I claim:

The ornamental design for a soda glass or similar article, as shown.
